United States Patent Office.

CHARLES E. WAREHAM, OF PORT WASHINGTON, WISCONSIN.

Letters Patent No. 77,554, dated May 5, 1868; antedated April 23, 1868.

IMPROVED ROTARY SCRUBBING-MACHINE.

The Schedule referred to in these Letters Patent and making part of the same.

TO ALL WHOM IT MAY CONCERN:

Be it known that I, CHARLES E. WAREHAM, of Port Washington, in the county of Ozaukee, and State of Wisconsin, have invented a new and improved Rotary Scrubbing-Brush and Mop; and I do hereby declare that the following is a full, clear, and exact description thereof, which will enable others skilled in the art to make and use the same, reference being had to the accompanying drawings, forming part of this specification, in which—

Figure 1 is an irregular vertical section of my improved rotary scrubbing-brush, taken in the lines xx , fig. 2.

Figure 2, a horizontal section taken in the line yy , fig. 1.

Similar letters of reference indicate like parts.

The object of this invention is to provide housekeepers with a convenient article for scrubbing and cleaning floors, or for use on board of ships to scrub the deck, or any similar purpose; and it consists in a box mounted on casters and side-wheels hung on an axis passing through the box, connected by gear with a horizontal brush, that touches the floor, and revolves to scrub the surface by drawing or pushing the box about. This rotary brush is very effective in scrubbing a floor, and saves much hard labor performed by women, while it does the work with greater cleanliness than the old method with a hand scrubbing-brush, which splashes the dirty water on all sides.

The box is so arranged, also, that it may be used as a sprinkler independently of the brush, or in connection with it, or may be changed into a mop for mopping the floor.

A represents a square wooden box, of any convenient size, mounted on three or more casters, $a a$, and resting also on two side-wheels, B B, which are hung on the ends of the horizontal shaft b , that passes through the box, and carries a bevel-wheel, c , engaging in a smaller bevel, c' , placed on the vertical shaft d , on the lower end of which is fixed a round scrubbing-brush, C, made of bristles, in the usual way, or of any other suitable material.

A bail or handle, e, is fastened to the side of the box for drawing it about on a floor, when the motion of the wheels B B will operate to revolve the brush C, and thus scrub the floor effectually by repeated movements backward and forward over the surface.

The box A has a partition, g, in it to form a water-chamber, D, in the upper part, and in the partition is a sliding valve, h, below which is fastened a perforated platform or screen, k, for sprinkling the floor by moving the box over the surface. The brush C may be so connected as to be raised when the sprinkler is used, and also for adjustment to the level of the wheels B B.

The brush C may be removed and a mop attached in its place for mopping the floor and wiping or drying it quickly after it has been scrubbed, or the same arrangement may be used for a permanent mop or brush, as desired.

Having described my invention, I claim as new, and desire to secure by Letters Patent—

The arrangement of the box A, mounted on wheels B B, in combination with the bevel-gear $c c'$, for operating a rotary brush or mop, substantially as and for the purposes herein described.

CHAS. E. WAREHAM.
